UNITED STATES PATENT OFFICE

2,382,681

LIQUID ATOMIZER AND DIFFUSER

Vernon Anthony Trier, London, England

Application June 22, 1944, Serial No. 541,580

10 Claims. (Cl. 261—78)

This application is a continuation-in-part of my application Serial No. 451,926 filed July 22, 1942, which has become, and now stands, abandoned.

This invention relates to apparatus for use in such operations as the sterilisation of the atmosphere of enclosed spaces, for example air raid shelters, sick rooms, hospital wards, school rooms, offices, domestic premises and the like, or the destruction of insect pests, involving the discharge into the atmosphere of an aerosol of a liquid having the necessary properties for the purposes of the operation, it being understood that by an "aerosol," as the term is used herein, is meant a suspension of the liquid sufficiently fine to be capable of remaining in the atmosphere for a long time, if not indefinitely, gradually diffusing itself therethrough.

A difficulty which has been experienced with apparatus of this description is that the aerosol, on discharge from the apparatus, tends to remain in the immediate neighbourhood thereof, with the result that the part of the atmosphere in the immediate neighbourhood of the apparatus becomes overcharged with the aerosol at the expense of another part more distant therefrom, at any rate until such time as the aerosol has had an opportunity of diffusing itself evenly throughout the space to be treated. In addition, inconvenience may be caused to the operator of the apparatus owing to an overconcentration of the aerosol in the immediate neighbourhood of the apparatus.

The object of the invention is to provide an improved form of apparatus of the description referred to which will be free from this disadvantage and will at the same time possess the necessary requisites for a really useful and satisfactory machine having in view the following considerations. Firstly, an apparatus for use in sterilising the atmosphere of, say, a hospital ward or an office or a room of a private house should be light and easily portable. It should also be capable of use by a person substantially unskilled in the handling and operation of mechanical devices, since in many cases the person called upon to use the apparatus will be a person in this category. It should also be capable of use in situations devoid of an electricity supply or other source of mechanical power, since even at the present time there are many possible situations of use of an apparatus of this description which are totally devoid of such a source of power, for example hospitals, schools and the like in the country. It should also be relatively

cheap to produce and it should be durable and fool-proof.

With these special considerations in mind, in conjunction with the general object of the invention as stated above, the invention provides a portable self-contained apparatus for sterilising the atmosphere and for like operations, comprising a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; an air pump connected to the atomising unit and operative to supply the same with air for its operation; a blower connected to a discharge nozzle adjacent the outlet and operative to deliver thereto a supply of air for the formation of an air blast from the nozzle effective to project the aerosol forwardly from the outlet into the surrounding atmosphere, and a manual means common to the air pump and the blower for operating the same.

In the present specification and the claims appended hereto, I employ the term "manual" to designate foot as well as hand operation.

It is found that such an apparatus eminently meets the object in view in this invention as set forth above, particularly if, as is preferred, the air pump of the machine is a pump of the piston-and-barrel type and the blower is a bellows or a large-diameter, short-stroke piston-and-barrel device, as with such a pump it is readily possible to provide a supply of air at the requisite pressure for the operation of the atomising unit and with such a piston-and-barrel device it is readily possible to produce the necessary large volume of air for the purposes of the air blast with a relatively small operative stroke of the blower and a correspondingly slow rate of operation thereof; also a bellows and similarly, a piston-and-barrel device of the character described is inherently a light form of mechanism for the purpose in hand and, moreover, is cheap to produce, requires little if any attention to maintain it in working order and has a long useful life—all essential attributes from the point of view of the requirements of a machine to satisfy the object in view in this invention.

According to a generally preferred form of the invention, hereinafter more particularly described, the air pump is a long-stroke hand-operated pump of the piston-and-barrel type uprightly standing from the stand, handle uppermost, and

pivotedly connected thereto at the lower end so as to have a freedom for swinging movement, variable (which term includes determinable) at the will of the operator, in a vertical plane as the pump is operated, and the blower is a bellows interposed between a stationary support on the stand and the barrel of the pump (or an arm thereon) so as to be operated by the swinging movements of the pump.

A principal advantage with such an arrangement is that assuming, as will generally be the case, the machine is designed to be worked upon the floor, the pump can be worked in the same way as a stirrup pump is worked, with one foot of the operator on the stand to keep the machine firmly down upon the floor and the handle of the pump gripped by the hand or hands and worked up and down at an easy rate—which, as is known, is an exceedingly simple and easily performed operation and one which does not quickly tire the operator. Moreover, the swinging movement of the pump in the machine which occasions the operation of the bellows is more or less a natural accompaniment of the up and down movement of the pump handle, owing to the characteristic tendency for the hands in working the pump to follow a path of movement which has a forward and backward component as well as an upward and downward component, and in consequence the operator is largely relieved of having to work the pump in some special manner in order to operate the bellows at the same time. Furthermore, it is possible, by simply varying the amplitude of the strokes of swinging movement of the pump to vary the volume of the air blast as described, for example to suit the size of the room or other space to be sterilised, while if it should be desired to cut out the air blast entirely, this can be accomplished by simply refraining from swinging the pump as it is being worked.

The invention will now be further described by way of example with reference to the accompanying drawings, in which:

Figure 1 is a side elevation and Figure 2 a plan view of a hand-operated apparatus;

Figures 3 and 4 are fragmentary enlarged views of the atomising unit and the pivoted end of the air pump, respectively;

Figures 5 and 6 are a side elevation and plan view respectively of another hand-operated apparatus;

Figure 7 is a side elevation of a foot-operated apparatus; and

Figure 8 is a fragmentary view illustrating a modification hereinafter described.

Like reference numerals refer to like parts in the various figures.

Referring first to Figures 1 and 2, the apparatus shown in these figures comprises an atomising unit 1, an air pump 2 for supplying air to the atomising unit for its operation and a bellows 3 for producing an air blast as hereinbefore referred to.

These parts are mounted on a stand 4 which rests on the floor and includes a portion 5 at the rear end upon which the operator rests one foot to hold the machine firmly down as it is being operated.

The pump 2 is pivotally mounted at 5 to the stand to swing backwardly and forwardly in a vertical plane towards and away from an upright 6 incorporated with the stand along with two side supports 7, 8 extending longitudinally thereof.

The atomising unit is carried upon the struc-

ture comprising the upright 6 and the two side supports 7, 8, which structure carries also an air reservoir 9 intervening in the path of the air between the pump and the atomising unit.

The bellows intervenes between the barrel of the air pump and the back of the upright 6 and is attached to both of these parts so as to be operated by the swinging movements of the pump about its pivot 5.

10 The atomising unit may be of any suitable design. In the particular embodiment of the invention shown in the drawings, it comprises an atomising chamber 10 in the lower part of which is placed a supply 11 of liquid to be atomised.

15 So positioned as to be above the surface level of this supply is a jet nozzle 12 drawing from the supply 11 and delivering a jet of the liquid in extremely finely divided form onto a baffle 13 which serves to break up some of the larger droplets of the spray into smaller droplets and at the same time to precipitate others, which fall or flow back into the supply of liquid in the lower part of the chamber from which the liquid thus returned is eventually re-sprayed on to the baffle

20 25 until the whole of the supply is used up.

The extremely fine mist or cloud of minute droplets of liquid flows upwardly in the chamber towards a discharge outlet 14 in the wall thereof at the top of the chamber, which it leaves in a

30 sensibly dry condition, that is, substantially unaccompanied by droplets of a size large enough to render the mist wet, having been effectively stripped of droplets of such a size partly by the action of the baffle 13 and partly by the action of

35 a second baffle 15 placed in the path of the mist between the first baffle and the outlet 14. There may be any necessary number of baffles in the chamber and these may be of any necessary form, according to requirements, it being essential for

40 the purposes of the apparatus that the product issuing therefrom shall be an aerosol in the sense hereinbefore defined unaccompanied by droplets of a size to render the product sensibly wet.

Also the spraying means may take any desired

45 form. In the particular embodiment of the invention shown, the jet nozzle constituting said means comprises a body 16 having an axial bore 17 extending completely through it and a radial bore 18 extending through the body from one

50 side thereof to a point beyond the axial bore which it, therefore, intersects in the manner shown in the drawings. Extending into the axial bore is a small-diameter tube 19, the lower end of which dips into the supply of liquid in the

55 lower part of the atomising chamber and is, of course, open thereto. The tube 19 extends across the bore 18 and terminates a little short of a spherical cavity 20 in the crown thereof. The bore 18 is of larger diameter than the bore 17

60 so as to provide a cavity 21 surrounding the end of the tube 19 where this extends across the bore. This cavity 21 is supplied with air under pressure from the air pump 2 by way of the air reservoir 9 and connecting piping 22, 23, the portion 22 of

65 this piping being flexible to accommodate the swinging movements of the pump and the portion 23 being connected to the body of the nozzle by a tubular connecting branch 24 screwed thereinto along the bore 18. The air on reaching the cavity

70 21 flows at high velocity into the spherical cavity 20 past the edge of the upper end of the tube 19 and thence out of the nozzle by way of the portion of the bore 18 leading from the cavity 20 to the surface of the nozzle. In doing so, it draws

75 liquid up the tube 19 and delivers it into the space

above the nozzle as a finely divided jet. It is found that a nozzle of this particular description is eminently efficient. As already remarked, however, any other construction may be employed without departure from the invention.

The air pump 2 is substantially of standard design. It comprises a long barrel 25 in which works a piston 26 connected by a rod 27 to a handle 28. The barrel 25 is closed at the lower end by a dish-shaped member 29 (see Figure 4) having on the underside a block 30 forming a bearing on the barrel for a fixed pivot pin 31 on the stand 4. Projecting from the member 29 is a branch 32 in which is a port passage 33 controlled by a non-return ball valve 34 and from which in turn is a tubular branch 35 communicating with the space behind the valve 34 and to which the piping 22 is connected. The pump is a single-acting force pump, the upward strokes being non-working strokes and the downward strokes working (compression) strokes, forcing the air past the valve 34 to the reservoir 9 and thence to the jet nozzle of the atomising unit.

The bellows 3 is also of standard construction. It comprises a pair of end members 36, 37 in which respectively are an inlet flap valve 38 and an outlet flap valve 39, and an intervening collapsible wall 40 connected to the end members. The valve 38 controls a port 41 in free communication with the atmosphere and the valve 39 controls a port 42 in communication with a cavity 43 in turn communicating with the bore of a nozzle 44 carried upon the upright 6 and directed into a space in the atomising chamber above the baffle 15 therein in the direction towards the outlet 14. As the pump 2 is swung about its pivot the bellows open and close and during the closing strokes force a copious supply of air to the nozzle 44, which issues therefrom as an air blast as hereinbefore referred to, operative to project the cloud of aerosol emerging from the atomising unit forwardly from the outlet 14 thereof.

Referring now to the embodiment of the invention illustrated in Figures 5 and 6, the machine of this embodiment is generally similar in construction and manner of operation to that of Figures 1 and 2. The only essential differences are as follow:

Firstly, the bellows is disposed below the atomising unit, being affixed to a shelf 45 extending across the space between the two side members 7, 8 and being interposed between this shelf and an arm 46 on the barrel of the pump, which arm, therefore, transmits the swinging movements of the pump to the bellows for the operation of the same. The bellows communicates with the air blast nozzle 44 by way of a pipe 47.

Secondly, the air reservoir 9 is positioned at one side of the structure comprising the upright 6 and the two side members.

Thirdly, the pump is pivoted to the back of the said upright 6 instead of to the stand 4, although if desired, it may be pivoted thereto as in the other construction.

Fourthly, the stand is provided with wheels 48 at one end to facilitate its transportation across the floor. Here again, however, these may be omitted, if desired. Also, similar wheels may be provided in the machine of Figures 1 and 2, if desired.

The foot-operated machine of Figure 7 comprises a compressed-air operated atomising unit 1, a foot-operated air pump 49 supplying operating air thereto and a bellows 3 for producing

an air blast, these parts being carried upon a stand 4 incorporating a structure 50 upon which the parts referred to are mounted. The machine is worked on the floor as in the case of the machines of Figures 1 and 2 and Figures 5 and 6.

The construction and manner of operation of both the atomising unit and the bellows is or may be the same as that in the machine of Figures 1 and 2 and will, therefore, not be repeated.

10 The air pump 49 is operated by a pedal 51 carried on the free end of one arm of a double-armed lever 52 pivoted at 53 to the structure 50. The other arm of the lever 52 extends forwardly from the pivot and has the reciprocatable end member 36 of the bellows connected to it, the other end member 37 of the bellows being connected to a bracket 54 incorporated in the structure 50. The lever 52 is normally urged in a clockwise direction about its pivot 53 by a spring 20 55 and is moved in the reverse direction by foot-pressure on the pedal 51.

The air pump 49 is a single-acting force pump and comprises a barrel 56 in which works a piston 57 on a rod 58 pivoted at 59 to the lever 52, 25 the barrel 56 being pivoted at 60 to a bracket 61 upstanding from the stand 4 and affixed thereto. At the inner end of the barrel 56 is a non-return outlet valve 62 similar to the valve 34 of the machine of Figures 1 and 2 and the 30 air on passing this valve flows on to the atomising unit via an air reservoir 9.

The air for the air blast flows to the nozzle 44 via a pipe 63.

According to a possible modification, a large-diameter short-stroke piston-and-barrel device may be used in place of a bellows in any of the machines of Figures 1 and 2, Figures 5 and 6 and Figure 7. One form of such a device is illustrated in Figure 8.

40 As there shown, the device, which is illustrated as employed in a machine otherwise in accordance with Figures 5 and 6, comprises a barrel 64 in which works a piston 65 on a rod 66 pivoted at 67 to the arm 46 on the air pump barrel and 45 extending through a guide 68 in the centre of an end member 69 of the barrel, the barrel being pivoted at 70 to a bracket 71 incorporated with the stand of the machine.

The device is single-acting and operates in the 50 same manner as the conventional force pump, the upward (i.e. outward) strokes being non-working strokes, during which air flows past the edge of the piston to the portion of the interior of the barrel beneath it, and the downward (inward) strokes being compression (working) strokes, during which the air flows out of the barrel by way of an outlet port controlled by a non-return valve 72, which may be similar to the valve 34 of the air pump of the machine.

60 It will be understood that although details have been given in the foregoing description of certain embodiments of the invention, the scope of the invention is not limited thereto. For example, as already indicated, the atomising unit 65 may be of any other construction than that described, as also may be the air pump and the blower. On the other hand, the form of these parts in the particular machines described is generally speaking a preferred form for reasons already stated herein.

70 It will also be understood that the term "manual means" as used herein and in the appended claims includes both hand-operated means and also foot-operated means, in contrast in either

case to power (e. g. electrically) -operated means.

Also, the term "stand" as used in the claims denotes the entire structure upon which the atomising unit, the air pump and the blower are carried.

What I claim as my invention and desire to secure by Letters Patent of the United States is:

1. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; an air pump connected to the atomising unit and operative to supply the same with air for its operation; said pump being of the reciprocating piston-and-barrel type; means for mounting said pump for pivotal movement with respect to said stand; a blower connected to a discharge nozzle adjacent the outlet and operative to deliver thereto a supply of air for the formation of an air blast from the nozzle effective to project the aerosol forwardly from the outlet into the surrounding atmosphere, and means common to the air pump and the blower for manually reciprocating the piston within the pump and for rocking the pump about its pivotal mounting, said means being effective to operate said blower.

2. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; a long-stroke hand-operated piston-and-barrel type air pump connected to the atomising unit and operative to supply the same with air for its operation, said air pump upstanding from the stand, handle uppermost, and being pivotally connected thereto at the lower end so as to have a freedom for swinging movement in a vertical plane as the pump is operated; and a blower having a reciprocating operative movement, connected to a discharge nozzle adjacent the outlet and operative to deliver thereto a supply of air for the formation of an air blast from the nozzle effective to project the aerosol forwardly into the surrounding atmosphere, said blower being arranged to be operated by the swinging movements of the air pump.

3. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; a long-stroke hand-operated piston-and-barrel type air pump connected to the atomising unit and operative to supply the same with air for its operation, said air pump upstanding from the stand, handle uppermost, and being pivotally connected thereto at the lower end so as to have a freedom for

swinging movement in a vertical plane as the pump is operated; and a bellows connected to a discharge nozzle adjacent this outlet and operative to deliver thereto a supply of air for the formation of an air blast from the nozzle effective to project the aerosol forwardly from the outlet into the surrounding atmosphere, said bellows being interposed between a stationary support therefor on the stand and the barrel of the air pump so as to be operated by the swinging movements of the pump.

4. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; a long-stroke hand-operated piston-and-barrel type air pump connected to the atomising unit and operative to supply the same with air for its operation, said air pump upstanding from the stand, handle uppermost, and being pivotally connected thereto at the lower end so as to have a freedom for swinging movement in a vertical plane as the pump is operated; and a bellows connected to a discharge nozzle adjacent the outlet and operative to deliver thereto a supply of air for the formation of an air blast from the nozzle effective to project the aerosol forwardly from the outlet into the surrounding atmosphere, said bellows being interposed between a stationary support therefor on the stand and an arm on the barrel of the air pump so as to be operated by the swinging movements of the pump.

5. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall through which the aerosol is discharged; a long-stroke hand-operated piston-and-barrel type air pump connected to the atomising unit and operative to supply the same with air for its operation, said air pump upstanding from the stand, handle uppermost, and being pivotally connected thereto at the lower end so as to have a freedom for swinging movement in a vertical plane, variable at the will of the operator, as the pump is operated; and a blower having a reciprocating operative movement, connected to a discharge nozzle adjacent the outlet and operative to deliver thereto a supply of air for the formation of an air blast from the nozzle effective to project the aerosol forwardly from the outlet into the surrounding atmosphere, said blower being arranged to be operated by the swinging movements of the air pump.

6. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; a long-stroke

hand-operated piston-and-barrel type air pump connected to the atomising unit and operative to supply the same with air for its operation, said air pump upstanding from the stand, handle uppermost, and being pivotally connected thereto at the lower end so as to have a freedom for swinging movement in a vertical plane, variable at the will of the operator, as the pump is operated; and a bellows connected to a discharge nozzle adjacent the outlet and operative to deliver thereto a supply of air for the formation of an air blast from the nozzle effective to project the aerosol forwardly from the outlet into the surrounding atmosphere, said bellows being interposed between a stationary support therefor on the stand and the barrel of the air pump so as to be operated by the swinging movements of the pump.

7. A portable self-contained apparatus for sterilising the atmosphere and for like operations, which comprises a stand and mounted thereon, an enclosed compressed-air operated atomising unit operative to convert a liquid, drawn from a supply thereof in the apparatus, into an aerosol and to deliver the latter, unaccompanied by droplets of a size sufficiently large to render it sensibly wet, into the surrounding atmosphere by way of an outlet in the wall of the unit; a long-stroke hand-operated piston-and-barrel type air pump connected to the atomising unit and operative to

supply the same with air for its operation, said air pump upstanding from the stand, handle uppermost, and being pivotally connected thereto at the lower end so as to have a freedom for swinging movement in a vertical plane, variable at the will of the operator, as the pump is operated; and a bellows connected to a discharge nozzle adjacent the outlet and operative to deliver thereto a supply of air for the formation of an air blast from the nozzle effective to project the aerosol forwardly from the outlet into the surrounding atmosphere, said bellows being interposed between a stationary support therefor on the stand and an arm on the barrel of the air pump so as to be operated by the swinging movements of the pump.

8. An apparatus as specified in claim 1, wherein the means common to the air pump and the blower includes a pedal-operated lever pivoted to the stand.

9. An apparatus as specified in claim 1, wherein the means common to the air pump and the blower includes a handle for manual actuation of the pump and for effecting manual operation of said blower.

10. An apparatus as specified in claim 1, wherein the blower is a bellows and is expanded and compressed by the means which also actuates the pump.

VERNON ANTHONY TRIER.
